MULTIPLE-FLAVOR VENDING MACHINE

Harvey T. Larimore, Congress Park, Ill., assignor
to Kalva Venders, Inc., Chicago, Ill., a corpora-
tion of Illinois

Application October 16, 1941, Serial No. 415,250

8 Claims. (Cl. 312—95)

My invention relates to vending machines and particularly coin-operated vending machines. The particular style of vending machine is one for delivering unit articles as for example, bottled beverages, and is so constructed that beverages of more than one flavor can be selected and dispensed from the same cabinet.

Among the objects of my invention is to provide a new and improved coin-operated vending machine which is so set up that it can deliver one articles at a time from one of a plurality of conveyors, the mechanism being such that after the coin has been deposited the purchaser can select which of the several conveyors he desires his purchase to be delivered from.

Another object of my invention is to provide a new and improved gravity-operated vending machine which is equipped with an indexing device manually operated and so constructed that only one article at a time is delivered from the conveyor to a delivery chute where the article is conducted to a vending position by means of gravity.

Still another object of my invention is to provide a new and improved vending machine for unit articles wherein the articles are moved partly by manual operation after the deposit of a coin and which includes a gear mechanism which begins to operate after delivery has started so that complete functioning of the machine will be assured for every coin deposited and exactly one article will be made available to the purchaser, the object being further to return the manually operated delivery means automatically to an initial position after completion of one delivery operation.

A further object of my invention is to provide a new and improved coin-operated vending machine which is simple and relatively inexpensive to manufacture and one which utilizes manual operation to index articles to be delivered one at a time and deposit them over a gravity-operated trap door adapted to open when the weight of an article is pressed upon it and to automatically close after the article has passed.

With these and other objects in view, my invention consists in the construction, arrangement and combination of the various parts of my device whereby the objects contemplated are attained as hereinafter more fully set forth, pointed out in my claims and illustrated in the accompanying drawings, in which:

Figure 1 is a top view of one embodiment of my device showing the relative position of a plurality of endless conveyors.

Figure 2 is a top view of my device shown in

Figure 1, partly in section and showing the indexing and delivery mechanism.

Figure 3 is a vertical view in section taken on the line 3—3 of Figure 2.

Figure 4 is a fragmentary plan view of another embodiment of my device, partly in section showing a different unlocking mechanism.

Figure 5 is a partial side view on line 5—5 of Figure 4 shown partly in section.

In the design of vending machines, it is frequently necessary that the purchaser of the articles to be vended be given some selection as to the particular article which he desires to buy. This is especially true in machines designed for vending bottled beverages. The taste of the public is usually such that more than one flavor of beverages must be dispensed by a machine if it is to have customer appeal. Machines have been designed in the past for making different beverages available to a purchaser by his own selection but it has been found that most machines of this type are quite cumbersome and become expensive to manufacture. Furthermore, machines designed for a multiplicity of flavors of beverages in the past whenever they have been constructed so as to be manually operated require so much force to shift the mechanism through numerous operations or such an amount of time in delivering a single article to the purchaser that they have frequently been discarded as too cumbersome for practical operation.

On the other hand, automatic machines have likewise been designed utilizing a power-actuated device built into a selective machine and the necessary mechanisms have become complicated to such a degree that the cost of construction is prohibitive. Therefore, as defined in the objects of this invention, the applicant's vending machine has been constructed to operate in a way which may be termed semi-automatic but which depends partly upon the manual operation of the purchaser to start delivery of the article purchased. The machine is simple in its construction and depends upon gravity to complete the delivery operation. By keeping the parts substantially simple, a plurality of conveyors each provided with a different flavor, for example, can be assembled in one machine without unduly multiplying the cost.

As shown in the drawings of the first embodiment of my invention, the vending machine includes an insulated housing 10 within which all of the articles to be vended may be kept prior to delivery. A storage space 11 may likewise be provided for a reserve supply of the articles to be

vended. Within the housing there are provided three separate and independently operated endless conveyors identified by the characters 12, 14 and 16. These conveyors as shown in Figures 1 and 3 have horizontal tracks 17, the rear ends of which are mounted upon a cross frame 18 and the front ends upon a cross frame 20. The rear ends of the conveyors are each provided with a toothed wheel 22 rotating about a stub shaft 24. At the front end, each endless conveyor is driven by a toothed wheel 26 which is secured to a drive shaft 28 journaled at the bottom in a bearing 30 on the cross frame 20 as shown best in Figure 3. Each track terminates at the cross frame 20 which is adjacent the point of deflection of the deflection of the conveyor chain by the toothed wheel 26. Each conveyor likewise is provided with a series of pins 32 spaced along the conveyor at intervals slightly greater than the width of articles which are to be carried upon it. As illustrated in Figure 1, these articles may be bottles 34 having a substantially cylindrical shape at the point where they are in contact with the pins.

The insulated casing 10 is provided with a top 36 which covers all of the endless conveyors. Above the top there is provided a sheet-metal housing 38 which supports a frame carrying the indexing and delivery mechanism. At the left end of the housing, as viewed in Figure 1, there is provided a coin-selecting mechanism 40 of a conventional sort not forming a part of this invention which has in it a coin slot 42 designed to receive coins or tokens and pass them to the working mechanism of my invention and a coin return slot 43 for rejected coins.

Beneath the coin-selecting mechanism there is a coin-actuated trip device which enables the coin to release the manually controlled indexing and delivery mechanism. The coin actuated trip device consists of a movable coin slot element 44 which has a coin slot 45 in vertical alignment with the coin slot leading from the coin-selector mechanism as best shown in Figure 2. A bracket 46 is attached to the coin slot at one end.

For holding coins in the coin slot there is provided a somewhat U-shaped rocker arm 48 which has a plate 50 at the left end as viewed in Figure 2 extending partly beneath the coin slot 45 and in fact forming a movable bottom for the slot. The rocker arm is pivoted about the element 51. At the other end, the rocker arm is provided with a stop arm 52 which is designed to abut against a shoulder 53, thereby limiting rotation of the rocker arm in a counter-clockwise direction. A voluntary coin return is also provided for, consisting of a push button (not shown) adapted to rotate the plate 50 in a clockwise direction around 51, allowing plate 50 to swing wide enough for the coin to drop past it by gravity into return chute and roll out the casing at 43.

Likewise pivoted about the point 51 is a lever element 54 which has attached to its left end, as viewed in Figure 2, a cam element 55 provided with a sloping face 56. Also secured to the lever 54 is a latch 57 positioned adjacent a shoulder 58 with which it may engage and disengage during certain steps in the vending operation. At its other end the lever is provided with an arm 59 secured by a coiled spring 60 to a pin 61. By means of the coiled spring the lever is normally retained in the position shown in Figure 2.

The operation of these various parts will be described later in conjunction with the machine as a unit.

Extending from the coin mechanism, as viewed

in Figure 2, is a slide bar 64 mounted upon a flat plate 65 and held in slidable contact thereto by means of keepers 66 positioned within the housing 38. A portion 67 of the slide bar carries the shoulder 58, previously described, and has also secured to it the bracket 46. Secured to the bracket 46 at one end is a long coiled spring 68 which at the other end is fastened to a pin 69. The spring normally tends to urge the slide bar 64 toward the right as viewed in Figure 2. This action tends constantly to keep the coin slot element 44 urged toward the right to its normal position as shown in Figure 2 where it can receive a coin from the coin selector. A single coin-actuated mechanism is provided for operating all of the plurality of endless conveyors.

The manual indexing and delivery mechanism for the conveyor nearest the coin slot includes a rod 70 provided with a handle 71 adapted to be grasped by an operator. The rod is slidably mounted at the point 72 in the housing 38 and at a corresponding point at the rear of the housing. Normally, the rod is held by a coiled spring 73 in a retracted position as shown in Figure 2. On one side of the rod is a toothed rack 74 and this is designed to mesh with teeth 75 of a toothed wheel 76. The wheel in turn rotates freely on a stub shaft 77 which is journaled at two points, one on the top 36 of the casing and the other at the flat plate 65 forming a part of the frame within the housing 38. It will be noted that the teeth 75 occupy approximately two-thirds of the circumference of the wheel 76. The other one-third of the wheel consists of a similar series of teeth forming projections and depressions 78 and the smaller section of the circumference is separated from the larger section by a pair of recesses 79 and 79' having a depth slightly greater than the depth of either the space between teeth or the depressions. Adjacent each wheel 76 there is provided a ratchet 80 pivoted at the point 81 and retained by a coiled spring 82 in the positions shown in Figure 2. It will be noted that the ratchet extends into the recess 79 in each of the wheels 76 when in normal position. There is also provided above each wheel a member pinned to the respective stub shaft and having thereon a series of three shoulders 83 spaced substantially 120 degrees from each other. On the upper surface of each wheel is a pawl 84 pivoted about the point 85 carried by the wheel and spring pressed into normal position by the leaf spring 86. The action of the pawl upon the shoulders is to provide a driving or indexing connection between the wheel and the stub shaft during a forward movement of the rod 70.

Likewise in this particular embodiment, there is a pinion 88 pinned to the stub shaft 77 and meshing with a second toothed wheel 89, as shown to best advantage in Figure 3. The second toothed wheel is pinned to the drive shaft 28.

As viewed in Figure 1, the opposite parallel sides of each endless conveyor are separated by a partition wall 94. There are also provided outside walls 106 set back from the front and it will be noted that the partition wall extends beyond the drive shaft 28 toward the front end of the machine where a portion 95 of the partition wall overlies the pins 32 as they round the bend at the front end of the endless conveyor. It is also important to note that the partition wall extends only to a point substantially above the tops of the pins so that they are free to pass beneath it as they pass round the bend.

Adjacent the front or delivery end of the con-

veyor the housing 10 is provided with a delivery pocket 86 which is formed by the walls of the housing 10 and the top 36. There is likewise provided a button 87 for the pocket closing the space between the front wall of the housing 10 and an intermediate wall 88 located rearwardly with respect to the front wall. In the bottom is an aperture 89, somewhat greater in diameter than the diameter of the largest bottle or cylindrical article to be dispensed. This aperture is located slightly to one side and near the front end of the conveyor as viewed in Figure 1. A trap door 100 hinged at the point 101 is spring pressed to a closed position as shown in Figure 3. A delivery passage 102 leads from the trap door downwardly and then outwardly toward the front of the housing. At the front, guard plate 103 partly closes the passage but has in it an opening 104 through which a delivered article can pass. At the lower side of the opening there is provided a shelf 105 which is designed to catch and retain an article after it has been delivered.

When the machine is set up to dispense more than one flavor of beverage, an interlocking mechanism is provided in order to prevent operation of more than one conveyor at a time. In addition to the slide bar 64, there is provided a slide bar 110 and another slide bar 112 in longitudinal alignment with each other. For example, the lefthand end 111 of slide bar 110, as viewed in Figure 2, abuts against the righthand end of slide bar 64 and the righthand end 113 of slide bar 110 abuts against the lefthand end of 114 of the slide bar 112. Another end 115 of slide bar 112 abuts against a stationary portion of the machine. It will also be noted that a portion of the righthand end of the slide bar 64 is cut on a slant providing an oblique face 64'. Similarly slide bar 110 has an oblique face 116 at the left end and 118 at the right end. Similar oblique faces 120 and 121 are provided on opposite ends of the slide bar 112.

Above the rod 70 there is attached a plate 65' which extends above the upper surface of the rod and lies in the same plane as the slide bars. Similarly the slide bar 70' has a plate 65'' attached to it and the slide bar 70'' has plate 65''' attached to its upperside. Each one of the plates 65', 65'' and 65''' has an oblique face 122 which has the same direction as the adjacent oblique face of the slide bars on the left as viewed in Figure 2. The right hand edge 123 of each plate 65', 65'' and 65''' extends in a direction parallel to the rods 70, 70' and 70'' so that it can pass by the end of the slide bar on the right side of each respective rod.

The sloping surfaces 116 and 120 are to provide a beveled clearance so that there will be no binding when the slide bars 110 and 112 are moved respectively from left to right after they may have been moved from right to left during the course of a dispensing operation. The movement of spring 68 returns them from left to right to normal position after operation.

An alternative construction is shown in Figures 4 and 5, which embodies a modified form of coin control and coin return. The general set-up of the conveyor mechanisms is the same in Figures 4 and 5 as that described in connection with Figures 1, 2 and 3 except that the movement of the conveyor is in reverse direction, made necessary by the absence of a reversing gear in connection with the manually actuating portion of the device. A bottle is tipped off the conveyor by means of an extension of the par-

tion on to a trap door in the same manner as previously described.

In the alternative construction, there is shown a housing 130 and a conveyor 131 beneath the housing on which are positioned pins 132. The conveyor is driven by a toothed wheel 133 which is pinned to a drive shaft 134 mounted within the housing. A manually actuated rod 135 is mounted by means of brackets 136 and 137 to the housing extending through the front wall and is provided with a knob 138, by means of which it can be operated manually. A coiled spring 139 is secured by means of a screw 140 at one end and to a stationary bracket 141 on the machine at the other end for automatically returning the rod to initial position. On one side of the rod is a rack 142 which meshes with teeth 143 of a pinion. The pinion rotates freely about the shaft 134. On the pinion a pawl 144 is pivoted at the point 145 and is continually urged in a clockwise direction by means of a leaf spring 146. The pawl is carried by and rotates with the pinion when it is rotated by means of the rack. When rotated, the pawl engages shoulders 147 which extend outwardly from a sleeve 148, in turn fixed to the shaft 134. The space between shoulders is equal to the amount of movement of the conveyor necessary to deliver one article. There are likewise provided a series of depressions and projections 149 similar to those previously described, cooperable with a ratchet 150 in order to prevent return of the delivery mechanism until a complete delivery cycle has been completed.

The rod 135 is provided with a plate 151 on the bottom side as described in connection with Figures 1, 2 and 3, which is adapted to slide between slide bars 152 and 153. The slide bars in turn are held by keepers 154 and 155.

Likewise within the casing, there is provided a coin selecting mechanism designated generally by the character 160 and within the mechanism is a coin slot 161 into which coins are deposited after having passed through the selecting mechanism. Beneath the coin slot is an elongated coin supporting element 165 pivotally mounted by means of a pin 166. The coin supporting element has an extension 167 at the other side of the pin 166. A coiled spring 168 attached to a bracket 169 continually urges the supporting element to the normal position shown in Figure 4, which is directly beneath the coin slot 161.

On the slide bar is a block 170 pivoted at the point 171 to the block and provided with a coin contacting finger 172, the end of which lies adjacent the coin slot. On the stationary portion of the machine is a locking element 173 adjacent the path of travel of the slide bar 152. On the block is provided a similar locking element 174 adapted to engage the first locking element. There is also provided an abutting end 175 which normally rests on top of the first-mentioned stationary locking element. A coiled spring 176 attached at one end to one side of the block and at the other end to a pin 177 normally holds the block so that the locking elements are in potential engaging positions. A second coiled spring 178 attached to the block at one end and to a stationary portion of the frame at the other normally holds the slide bar 153 in a retracted or normal position.

Likewise on the coin contacting finger 172 is provided recess 179, the function of which will be described under the topic "Operation." In Figure 5 are shown details of a coin return

mechanism attached to the side of the coin selecting unit 160. The coin return mechanism consists of a manually depressible element 180 pivotally mounted at the point 181 to the coin selecting mechanism and provided with a spring 182 for maintaining it in a normal position. Attached to the manually depressible element is a reciprocating lever 183 pivotally mounted at the point 184 at one end and having an elongated slot 185 at the other end within which is positioned a pin 186, in turn secured to a pivoted arm 187. The arm 187 is pivotally mounted by means of a pin 188 to the side of the coin selecting mechanism. A coiled spring 189 is attached to the lowermost end 190 of the lever 183 and to the pin 186 on the arm 187. A coin return passage 192 is shown at the lower lefthand side of Figure 5, which is adapted to receive coins which are to be returned to the purchaser. Coins roll down the slot and pass outwardly from the machine to a return receptacle 193. Likewise adjacent the bottom of the slot 161 is a coin retaining purse 194 within the machine which collects coins which have been accepted for the sale of articles which are vended.

Operation of Figures 1, 2 and 3

In operation of the first described embodiment of my invention, a coin or slug is deposited in the coin slot 42 and after passing through a suitable coin selecting mechanism passes into the coin slot 45 in the coin slot element 44, as best shown in Figure 2. The coin while in the coin slot 45 rests upon the plate 50 in operative position. After the coin has been thus deposited, the operator grasps the handle 71 of the rod 70 and pulls it forward against the tension of the spring 73.

When the rod 70 moves forward it engages the slide bar 64 and by means of the oblique face 64' forces the slide bar in a direction from right to left as viewed in Figure 2. Movement in this direction forces a coin held in the coin slot 45 against the sloping surface 56 of the cam 55 and action of the coin against the sloping surface thereby pivots the lever arm 54 in a clockwise direction about the pin 51. The lever arm being thus pivoted causes the latch 57 to be raised out of contact position with the shoulder 58 before contact is actually made and permits continued free movement of the slide bar in a leftward direction. The bar continues moving leftward until the coin slot element passes beyond the leftmost edge of the plate 50 and at that point the coin drops down into a collecting purse (not shown). This occurs at the outermost thrust of the rod 70 and simultaneously with delivery of an article from the end of the conveyor. The operator can then release the handle 71, the spring 73 will return the rod to initial position and the spring 68 will likewise return the slide bar 64 and attached mechanism to its normal position wherein it will be locked against a subsequent vending operation by reason of the latch 57 being in potential engagement with the shoulder 58. It will be apparent that unless a coin is dropped into the coin slot 45 so that it can engage the sloping surface 56, there will be no unlocking of the slide bar 64 and it will be impossible to pull the rod 70 outward through an indexing and delivery operation.

Furthermore, the relationship of the teeth on the wheel 76 with the rod 70 is such that for each reciprocating movement of the rod, the con-

veyor is advanced a distance just sufficient to push one article from the delivery end into the delivery pocket. As the rod moves forward in the manner just described, the rack 74 by reason of meshing with the teeth of the wheel 76 rotates the wheel 76 in a clockwise direction. Since the pawl 84 is carried by the wheel 76, clockwise rotation of the wheel 76 will rotate the pawl 84 and force it against the shoulder 83. Rotation of the member carrying the shoulder 83 will rotate the stub shaft 77 and the pinion 88 which in turn will rotate the second wheel 89 thereby imparting to the wheel 89 a counterclockwise rotation. This means that the drive shaft 28 rotates counterclockwise and causes the leftmost parallel track of the endless conveyor to move from the rear toward the front of the machine as viewed in Figure 1.

As the conveyor thus advances, one of the articles 34 carried by it is pushed by the respective pin 32 into the delivery pocket 96. The article is prevented from continuing on around the end of the conveyor by reason of the interposition of the portion 95 of the partition wall. The article strikes against the wall 95 and is thus knocked from the conveyor into the delivery pocket. In the pocket the article falls upon the trap door 100 and due to its own weight, forces the trap door open and passes downwardly into the passage 102, through which it is conducted by gravity to the shelf 105. Here the operator can take hold of and remove the article from the machine.

During the indexing and delivery operation as the wheel 76 rotates, the ratchet 80 is pivoted about the point 81 in a counterclockwise direction and the end initially received within the recess 79 successively engages the projections 78 on the smaller section of the wheel's circumference. The ratchet thus serves to prevent reverse rotation of the wheel once the delivery operation starts. The wheel 76 can only be rotated in a clockwise direction until the ratchet 80 is received in the second recess 79' at completion of a single vending operation.

After this has happened, the ratchet can be pivoted in a reverse or clockwise direction as the wheel 76 reverses and returns to normal position. During the return rotation of the wheel in a counterclockwise direction as viewed in Figure 2, the pawl 84 is carried around and eventually pivots over the top of the next successive shoulder 83 and engages it on the opposite side preparatory to the next vending operation.

As shown in the drawings, the vending machine is set up to dispense three different flavors of bottled goods, though it is, of course, to be understood that any reasonable number of different flavors could be included equally well. In order that only one article from one conveyor may be delivered for the deposit of a single coin, an interlocking mechanism between the respective manually operated indexing and delivery mechanism is necessary. When in operation, the locking mechanism is so shifted that when one rod 70 is pulled forward, neither of the other rods can be pulled forward at the same time. This is accomplished by means of the previously described sliding bars 64, 110 and 112. When, for example, the rod 70 at the lefthand end of the machine is pulled forward, setting in operation the indexing and delivery mechanism for its respective conveyor, the slide bar 64 is moved from right to left. This is accomplished by means of the coacting oblique faces on the line 64'. It will be observed

that the plate 65', fastened to the upperside of the rod 70, is drawn forward with it when the rod is pulled forward. The plate thus moved will be drawn past the left-end face 111 of the slide bar 110, and the bar will remain locked in position. Similarly, the slide bar 112 by reason of having its lefthand end 114 abutting against right hand end 113 of member 110, will be locked in position. When this is true, neither of the rods 70' or 70" to the right of the rod 70 can be drawn forward by reason of the fact that their respective plates 65" and 65''' will abut against the oblique ends of the stationarily held slide bars which thereby lock the rods in normal position.

If, for example, the middle rod 70' is being pulled through an indexing and delivery movement, the two outside rods 70 and 70" will be locked in their respective normal positions. The rod 70" will, of course, be locked by reason of slide bar 12 being held in normal position when the plate 65" is moved past the end 114. Movement of the plate 65" in a forward direction will push the slide bar 110 from right to left by action of the oblique faces at 64" against each other. When slide bar 110 moves underneath the rod 70, it will be placed in the path of the plate 65' and thereby prevent the rod 70 from being pulled forward. Therefore, only the middle conveyor mechanism can discharge an article to its respective delivery passage. Movement of the slide bar 64 by the endwise thrust of the slide bar 110 will actuate the coin mechanism in the regular way.

When there is no coin in the coin slot 45, the slide bar 64 will be locked in position as previously described by reason of the shoulder 58 coming into engagement with the latch 57. When the slide bar 64 is locked in position, it will likewise lock slide bars 110 and 112 in position and none of the manually actuated rods can be pulled forward through a dispensing operation.

Operation of Figures 4 and 5

In order to vend an article by operation of the alternative mechanism shown in Figures 4 and 5, a coin C is inserted into the coin selecting mechanism from which it passes into the coin slot 161, which in this instance is stationary at all times. There the coin is supported edgewise on the coin supporting element 165, as shown both in Figures 4 and 5. When the coin has reached this position, the knob 138 is drawn outwardly, moving the rod 135 and rack 142, which in turn rotates the conveyor mechanism and advances an article on the conveyor to a delivery position. Meanwhile, the plate 151 on the underside of the rod 135 shifts the slide bar 152 along a path on the upper surface of a supporting plate 200 from right to left in the manner described in connection with Figures 1, 2 and 3. As the slide bar moves toward the left, the coin contacting finger 172 engages the side face of the coin C before the locking element 174 engages the corresponding locking element 173. As the finger contacts the coin, the block 170 is rotated in a clockwise direction about the point 171. The locking element 174 is lifted out of a position where it can engage the element 173.

As the slide bar continues to pass toward the left, a side element 195 of the coin slot extends into the recess 179 and engages the coin contacting finger. As the finger, together with the slide bar 152, continues to move toward the left, contact of the side of the coin slot with the finger lifts the finger out of engagement with the coin. The coin thereafter remains entirely free within

the slot 161. As the slide bar passes to the left-hand end of its movement, it engages the extension 167 of the coin supporting element, moves it from the solid line position shown in Figure 4 to the dotted line position there shown. With this movement, the coin supporting element passes from beneath the slot 161 to the lefthand side thereof, as viewed in Figure 5 and the coin released from this support, passes into the purse 184 for collection.

As soon as the vending operation has been completed, the spring 178 returns the slide bar 152 to its initial position and the coiled spring 176 rotates the block 170 back to its initial position where the locking elements 173 and 174 are again in position for potential engagement.

If no coin has been inserted and the manually operated rod 135 is pulled outwardly, the coin contacting finger will move to a position where the side 195 of the coin slot is positioned within the recess 179. This will not occur before the locking elements 173 and 174 become engaged. The mechanism will, therefore, be locked against a delivery operation.

Under circumstances where the prospective vendee, after depositing his coin, does not wish to complete a vending operation, the coin may be voluntarily returned to the purchaser by manipulation of a suitable means. When return of the coin is desired, the operator depresses the manually depressible element 180 by means of a push button 197. This in turn shifts the lever 183 downwardly, as viewed in Figure 5. During its movement downward, the lever shifts the arm 187 in a counterclockwise direction about its pivot point 188 until the arm assumes the dotted position 187' shown in Figure 5. At this point, the coin supporting element 165 will be in the dot-and-dash position 165' shown in Figure 4. When the coin supporting element has been moved to the righthand side of the coin slot 161, as viewed in Figure 5, support for the coin C will have been removed and the coin will pass out of the slot into the coin return passage 192, down which it will roll to the coin return slot 193.

By making a resilient, loose connection between the lower end of the lever 183 and the pivoted arm 187, a freedom of movement is provided which prevents binding of the parts, especially under circumstances where the manually depressible element is given a sudden blow in order to effect return of the coin.

There has thus been provided a dispensing mechanism wherein the working parts have been reduced in number so that substantially a minimum number of them are used for indexing a conveyor and moving it through a dispensing operation a sufficient distance only to place an article carried thereon into such a position that the remaining part of the dispensing operation is accomplished by gravity acting upon the article itself.

Some changes may be made in the construction and arrangement of the parts of my device without departing from the real spirit and purpose of my invention, and it is my intention to cover by my claims any modified forms of structure which may be reasonably included within their scope.

I claim as my invention:

1. In a dispensing machine for articles, an insulated casing, a horizontally positioned endless conveyor in said casing including spacers for engaging and impelling said articles toward a discharge location at one end thereof, wall portions for said casing forming a pocket adjacent the

discharge end and a bottom in the pocket located below the level of the conveyor having an aperture therein, a trap door normally spring pressed to a position closing said aperture, said casing having a normally open delivery recess communicating with the trap door aperture and a shelf therein for retaining said articles after delivery in a position accessible to an operator, and means connected to the conveyor having an indexing device operative to move the conveyor during each operation thereof to an amount sufficient to deliver one article at a time.

2. In a dispensing machine for articles, as insulated casing, a horizontally positioned endless conveyor in said casing including spacers for engaging and impelling said articles toward a discharge location at one end thereof, said conveyor having a reverse direction at said discharge end, wall portions for said casing forming a pocket adjacent the discharge end and a bottom in the pocket located below the level of the conveyor having an aperture therein, a trap door normally spring pressed to a position closing said aperture, a delivery passage below said aperture, said casing having a normally open delivery recess communicating with the passage and a shelf therein for retaining said articles after delivery in a position accessible to an operator, and manually actuated means connected to the conveyor having an indexing device operative to move the conveyor during each operation thereof to an amount substantially equivalent to the distance between adjacent spacers for delivering one article at a time.

3. A vending machine for articles comprising a frame, a conveyor and an actuating mechanism therefor, said actuating mechanism including a manually operated rod slidably mounted on the frame and spring retained in a normal retracted position, a rack on said rod, a vertical stub shaft in the frame having a wheel thereon and rotatable relative thereto, said wheel having one portion of its circumference meshing with the rack, a series of projections and depressions in the remaining portion and a pair of recesses separating the ends of said portions, a pivoted ratchet spring pressed in normal position within one of said recesses serving during rotation of the wheel to prevent partial reverse motion until said ratchet enters the other recess, a member attached to the stub shaft having shoulders thereon at spaced angular intervals and means on the wheel engageable with the shoulders to drive said stub shaft, a drive shaft geared to said stub shaft and connected to the conveyor, said conveyor having an endless track comprising a flexible conveying element in driving relationship with the drive shaft and having spaced projections for impelling said articles to a discharge station, and a mechanically releasable lock normally holding said rod in inoperative position.

4. In a vending machine for articles comprising a frame, a conveyor and an actuating mechanism therefor, an improved actuating mechanism including a manually operated horizontal rod slidably mounted on the frame and spring retained in a normal retracted position, a rack on said rod, a vertical stub shaft in the frame having a wheel rotatable thereon, said wheel having substantially two-thirds of its circumference toothed and meshing with the rack, a series of depressions and projections in the remaining third and a pair of recesses separating the larger portion from the smaller portion of the circumference, a pivoted ratchet spring pressed in normal position

within one of said recesses serving during rotation of the wheel to prevent an intermediate partial reverse motion of said wheel until said ratchet enters the other recess, means anchored to the stub shaft having shoulders spaced at 120° angular intervals and a spring-pressed dog on the wheel engageable therewith, a drive shaft geared to said stub shaft and connected to the conveyor, said conveyor having a horizontal endless track comprising a flexible conveying element in driving relationship with the drive shaft and having projections spaced thereon at intervals corresponding to a 120° angular rotation of said wheel for impelling said articles to a discharge station, a deflector extending over the conveyor for removing articles from the conveyor and a mechanically releasable lock normally holding said rod in inoperative position.

5. In a vending machine for dispensing articles having a coin release, an actuating mechanism, a plurality of endless conveyors for said articles, and an insulated casing for housing the conveyor, an improved actuating mechanism comprising a frame positioned above the casing, a hand operated axially slidable rod positioned horizontally on the frame having an end adapted to be grasped by the operator, said rod having a series of teeth extending therealong in the form of a rack, a shaft and pinion mechanism for translating movement of the rod to the conveyor, said conveyor being positioned horizontally in the casing and having spaced projections thereon for propelling said articles to a discharge location, a normally closed trap door in the casing adjacent and below the discharge end of the conveyor communicating with the outside of the casing and a delivery recess for receiving delivered articles.

6. In a vending machine for dispensing a variety of types of units, a plurality of endless conveyors one for each type of unit and an insulated casing for housing the conveyors, an improved actuating mechanism including a frame, a plurality of hand operated axially slidable rods positioned horizontally on the frame having an end of each adapted to be grasped by an operator, each said rod having a series of teeth extending along one side in the form of a rack, a series of shafts and pinions for translating movement of each rod through a drive shaft to its respective conveyor, said conveyors being positioned horizontally in the casing and having projections thereon for propelling said units to a discharge location, a normally closed trap door in the casing adjacent and below the discharge end of the conveyor communicating with the outside of the casing and a delivery recess for receiving delivered units, said actuating mechanism having an interlocking mechanism shiftable by each respective shaft during a dispensing movement into locking engagement with all the remaining shafts.

7. In a vending machine for dispensing a variety of types of units, a plurality of endless conveyors one for each type of unit, an insulated casing for housing the conveyors, and an actuating mechanism including a frame positioned above the casing, a plurality of hand operated axially slidable rods, positioned horizontally on the frame having an end of each adapted to be grasped by an operator, each said rod having a series of teeth extending along one side in the form of a rack, a series of shafts and pinions for translating movement of each rod through a drive shaft to its respective conveyor, said conveyors

being positioned horizontally in the casing and having projections thereon for propelling said units to a discharge location.

8. In a vending machine for dispensing a variety of types of units, a plurality of horizontal endless conveyors one for each type of unit, an insulated casing for housing the conveyors, and an actuating mechanism including a frame positioned above the casing, a plurality of hand operated axially slideable rods, positioned horizontally on the frame having an end of each terminating in a knob, each said rod having a series of teeth extending along one side in the form of a rack, a plurality of vertical stub shafts mounted in the frame and a primary toothed wheel loose on each stub shaft meshing one respectively with each rack, a unidirectional connection between the wheel and the shaft, a pinion fixed on each shaft, a plurality of vertical drive shafts positioned one adjacent each rack and a secondary toothed wheel mounted one on each

drive shaft meshing respectively with the adjacent pinion, each said drive shaft having a portion thereof extending downwardly into the casing and having a drive wheel attached thereto, 5 said horizontal endless conveyors being positioned in the casing one connected to each said drive wheel, projections on the conveyor spaced apart a distance in excess of the width of each unit for propelling said units to a discharge location, a deflector at said location for removing said units from the end of the conveyor, a normally closed trap door in the casing adjacent and below the discharge end of the conveyor communicating with the outside of the casing and a delivery recess for receiving delivered units, said actuating mechanism having an interlocking mechanism shiftable by each respective shaft during a dispensing movement into locking engagement with all the remaining shafts thereby limiting the dispensing operation to one unit at a time.

HARVEY T. LARIMORE.
